(57) CLAIM

The ornamental design for fruit picker adapted to be pole mounted, as shown and described.

DESCRIPTION

FIG. 1 is a perspective view of a fruit picker adapted to be pole mounted according to the present invention with fragmentary portions of an associated pole and collector net shown in phantom lines as not forming a part of the invention.

FIG. 2 is a top view of the fruit picker adapted to be pole mounted shown in FIG. 1.

FIG. 3 is a right elevational view of the fruit picker adapted to be pole mounted shown in FIGS. 1-2.

FIG. 4 is a front view of the fruit picker adapted to be pole mounted shown in FIGS. 1-3.

FIG. 5 is a rear end view of the fruit picker adapted to be pole mounted shown in FIGS. 1-4; and,

FIG. 6 is a bottom view of the fruit picker adapted to be pole mounted shown in FIGS. 1-5.
